UNITED STATES PATENT OFFICE.

GEORGE B. HEATH, OF ST. LOUIS, MISSOURI.

APPARATUS FOR MAKING CONCRETE POLES.

Application filed August 6, 1925. Serial No. 48,524.

This invention relates generally to apparatus for making concrete poles and, more particularly, to a certain new and useful improvement in such apparatus of the type in which the pole is shaped and formed under the action of centrifugal force.

In pole making machines of the class mentioned, it is essential for the production of poles of symmetrical form that the mold shall rotate evenly and without vibration and be rigidly centered relatively to its rotating mechanism. To this end, my invention has for its chief object the provision of an apparatus of the type stated in which the mold-containing shell or casing and its supporting structure are of efficient construction for shell rotation with minimum vibration and in which the mold and its containing shell are adapted for interengaging relation for effecting both rotation, and uniform centering within the shell, of the mold during the rotation of the shell.

It is also desirable in apparatus of this type for economical quantity production that the mold be conveniently removable from its containing-shell, and my invention has hence for another object the provision of such apparatus in which the mold and its shell are adapted for such interlocking relation for substantially unitary rotation without the employment of clamps or other such devices, thereby permitting ready and convenient removal of the mold.

My invention has for a further object the improvement and simplification generally of apparatus of the type mentioned.

And with the above and other objects in view, my invention resides in the novel features of form, construction, arrangement, and combination of parts hereinafter described and pointed out in the claims.

In the accompanying drawings,

Figure 1 is an elevational view of a concrete pole made in and by my new apparatus;

Figures 2 and 3 are enlarged transverse sectional views of the pole taken approximately on the lines 2—2 and 3—3, Figure 1, respectively;

Figure 4 is a longitudinal sectional view of a concrete pole making apparatus embodying my invention, showing the mold in side elevation, partly broken away; and

Figures 5 and 6 are enlarged transverse

sectional views of the apparatus taken approximately on the lines 5—5 and 6—6, Figure 4, respectively.

Referring now more in detail and by reference characters to the drawings, which illustrate a preferred embodiment of my invention, A indicates the bed-plate of the apparatus, which is semi-cylindrical in section and of suitable linear and diametrical dimensions, integral with or otherwise rigidly fixed to which are standards 1, 1, adapted to be bolted or otherwise fixed to a floor or other supporting surface. Provided upon the inner or convexed face, and suitably spaced longitudinally, of plate A, are circumferential ribs 2, to and upon which are rigidly and suitably fixed outer race-rings 3.

Disposed lengthwise of and horizontally over the bed-plate A and through the several rings 3, is a tubular shell B composed preferably of companion semi-cylindrical sections 4, 4, rigidly and permanently bolted or otherwise fixed together at their meeting edges, as best seen in Figure 5. Provided or formed circumferentially upon the outer face or periphery of shell B, are ribs 5 corresponding in number and longitudinal spacing with the ribs 2 of plate A. Fixed on the ribs 5 are race-ring 6 companion to rings 3, the rings 3 and 6 being adapted with the interposed balls or rollers 7 to provide efficient anti-friction bearings for supporting the shell B for axial rotation over the bed A. Bolted or otherwise fixed at their ends to bed A and embracing substantially the upper half of shell B in alignment registration with the bed-ribs 2, are securing or retaining-straps 8. Intermediate its ends, shell B has a crowned portion or band 9, over which from any suitable source of power (not shown) and accommodated by registering apertures, as at 10, 10, as best seen in Figure 6, in the bed-plate A and its standard 1, runs a driving-belt 11 for rotatably actuating the shell B.

The supporting-structure for shell B is relatively simple, yet firm and rigid, and enables rotation even at high speeds of shell B with minimum vibration.

Shell B is plain and smooth upon its inner periphery, and adapted to lengthwise fit for removal within shell B, is a mold C. This mold C, which may have any suitable configuration as may be desired in the fin-

ished pole, preferably comprises and is constructed of a pair of companion approximately semi-cylindrical sections 12 formed at their lengthwise margins or meeting edges with outwardly presented flanges 13 adapted to receive fastening bolts or the like 14 for detachably securing the mold-section 12 operatively together.

D designates a pole produced or made in the present mold C and, as a consequence, conforms in external configuration with the internal configuration of mold C. In the production of poles D, which are preferably of re-inforced construction, the re-inforcing frame or members and a suitable quantity of soft, plastic, or so-called liquid concrete or other cementitious mixture are placed and properly distributed within the mold C. The mold C, whose ends are closed by opposite end-walls 15, 15, is now lengthwise slidably disposed within and for rotary actuation with, shell B, in which actuation under the action of centrifugal force the charge is thrown and moves outwardly and lines the mold and upon solidification forms a hollow or tubular pole, such as the pole D, conforming in outer configuration, as stated, with the inner configuration of the mold-sections, the water and other lighter constituents of the charge coming to the inner surface of the tubular pole and being suitably removed, as through an aperture 16 in one of the mold end-walls 15. In order, however, that the finished poles D shall be uniform and symmetrical, it is essential, as I have mentioned, that the mold C shall be rigidly held in centralized or co-axial position within its shell or holder B. To such end, the shell B longitudinally tapers in diameter, as shown, and integrally or otherwise rigidly formed or provided upon the mold C, which preferably is also as a whole of tapering form and construction, is a series of circumferentially disposed annular or ring-shaped walls 17 suitably spaced longitudinally of the mold and being gradually of reduced diameter relatively to and corresponding with the tapering diametrical dimensions of shell B. It will hence be evident that, as the mold C is slidably fitted within the shell B, the several walls 17 engage wedgewise with the tapering shell B and not only frictionally secure the mold C and shell B together for rotation substantially as a unit, but also firmly and rigidly retain the mold C properly centralized within shell B for the production of symmetrical and uniform poles D. Thus I efficiently accomplish by my apparatus the objects hereinbefore stated. I might add that, in the production of poles D, a core 18 is suitably imbedded in the liquid concrete, by which, upon removal, an opening, as at 19, is formed in the finished pole for the entrance of electric wires and the like. It will be obvious that the several walls 17 also strength-

en the mold-sections 12 from buckling or distortion, and that the shell B readily accommodates molds C of varying length and dimensions for the production of poles D of varying size.

I am aware that changes in the form, construction, arrangement, and combination of the various parts of my apparatus may be made and substituted for those herein shown and described without departing from the nature and principle of my invention.

Having thus described my invention, what I claim and desire to secure by Letters Patent is:

1. In a concrete-pole making apparatus, a supporting bed and an elongated tubular holder-shell mounted for rotation on the bed, in combination with a separate elongated mold removably disposed endwise within the shell, and a series of spaced circumferential walls fixed only on the mold and removable with the mold from the shell adapted for engagement at their outer margin with the wall of the shell for centralizing the mold within the shell.

2. In a concrete-pole making apparatus, a supporting bed and an elongated tubular holder-shell mounted for rotation on the bed, in combination with a separate elongated tapering mold removably disposed endwise within the shell, and a series of spaced circumferential walls of gradually reduced diameter fixed only on the mold and removable with the mold from the shell adapted for engagement at their outer margin with the wall of the shell for centralizing the mold within the shell.

3. In a concrete-pole making apparatus, a supporting bed and an elongated tubular tapering holder-shell mounted for rotation on the bed, in combination with a separate elongated tapering mold removably disposed endwise within the shell, and a series of spaced circumferential walls of gradually reduced diameter fixed only on the mold and removable with the mold from the shell adapted for engagement at their outer margin with the wall of the shell for centralizing the mold within the shell.

4. In a concrete-pole making apparatus, an elongated tubular rotary holder-shell, in combination with a separate elongated mold removably insertable endwise within the shell, and means fixed only on the mold and adapted for engagement at their outer margin with the wall of the shell for wedgewise securing the mold removably within the shell.

5. In a concrete-pole making apparatus, an elongated tubular rotary holder-shell, in combination with a separate elongated tapering mold removably insertable endwise within the shell, and a series of spaced circumferential walls of gradually reduced diameter fixed only on the mold and adapted

for engagement at their outer margin with the wall of the shell for wedgewise securing the mold removably within the shell.

6. In a concrete-pole making apparatus, an elongated tubular rotary holder-shell tapering from end to end, in combination with a separate elongated mold also tapering from end to end removably insertable endwise within the shell, and a series of spaced circumferential walls of gradually reduced diameter fixed only on the mold and adapted for engagement at their outer margin with the wall of the shell for wedgewise securing the mold removably within the shell.

15 7. In a concrete-pole making apparatus,

a semi-cylindrical horizontally disposed supporting bed, a tubular shell mounted for axial rotation upon the bed, and means comprising a driving-member running over the shell for rotarily actuating the same. 20

8. In a concrete-pole making apparatus, a semi-cylindrical horizontally disposed bed-plate, annular bearings mounted upon the bed-plate, a tubular shell disposed lengthwise for rotation upon and through said 25 bearings, and means for rotarily actuating the shell.

In testimony whereof, I have signed my name to this specification.

GEORGE B. HEATH.
